HEAD LAMP

Charles W. Anklam, Detroit, Mich., assignor to
 C. M. Hall Lamp Company, Detroit, Mich., a
 corporation of Michigan

Application January 16, 1939, Serial No. 251,243

5 Claims. (Cl. 240—41.5)

In the present state of the art of vehicle head-lighting, it has become increasingly important to distribute the light of the projected beam according to a predetermined pattern, such as to 5 secure the best illumination of the road with the avoidance of glare in the eyes of passing motorists. One method of accomplishing this result is to place in front of the lamp a lens subdivided into small areas, which are fashioned to differentially refract the portions of the beam passing therethrough. The refraction is through prisms and flutes some of which are inclined horizontally and others vertically, the combined effect being 10 to increase the light intensity in certain portions of the pattern, and to diminish the intensity and diffuse the light in other portions. However, to make this construction effective in road lighting, the beam must be properly directed, both with respect to a vertical and a horizontal plane. It is 15 also customary with certain makes of motor vehicles, to place the lamp within the fender or some other fixed part of the vehicle body. This necessitates adjustment means by which the projected beam may be properly directed without disturbing the connection between the lamp and body.

It is the primary object of the invention to obtain a construction of lamp which facilitates such adjustment. It is a further object to provide for 20 independent adjustments respectively in vertical and horizontal planes and further to obtain various other advantages. With these objects in view, the invention consists in the construction as hereinafter set forth.

35 In the drawings:

Figure 1 is a vertical central longitudinal section through my improved lamp as mounted within the fender of a motor vehicle;

Figure 2 is a horizontal section on line 2—2 of 40 Figure 1;

Figure 3 is a vertical section on line 3—3 of Figure 1;

Figures 4 and 5 are sections respectively on line 4—4 of Figure 2 and line 5—5 of Figure 1;

Figure 6 is an elevation of the lens;

Figure 7 is an elevation of the locking means for the bezel member.

As illustrated in Figure 1, A is a portion of the fender, or other part of a motor vehicle body 50 and B is a lamp housing mounted within said fender in fixed relation thereto. C is the light projecting unit within the housing B, which comprises a concave or parabolic reflector D, a lens E and light producing means (not shown) adapted to be properly focused with respect to the reflector. As specifically shown, the lens E is permanently sealed to the reflector D through the medium of a clamping ring D' and sealing gasket D''. The Ring D' has a radially extending flange 55 D³ engaging the reflector, while the outer end of

said ring is peened as indicated at D⁴ to engage an annular shoulder E' on the lens E. It is to be understood that the lamp bulb is placed within the reflector and properly focused in relation thereto prior to the sealing of the lens. However, this specific construction of lamp is not an essential part of the instant invention.

As has been stated, it is the primary object of the invention to provide for angular adjustment of this light projecting unit independently in vertical and horizontal planes, which is accomplished by the following construction. Connected to the unit C is an annular member F which has a portion of F' of segmental spherical form constituting a bezel surrounding the lens and engaging the shoulder E'. G is another annular member having a radially inwardly extending flange G' in rear of the flange D³ and seated on a plurality of lugs D⁵ thereon. These lugs have portions projecting outward through apertures in the flange G' so as to prevent relative rotation of said flange and the flange D'. The annular members F and G are locked to each other by a plurality of resilient members H, which are substantially U-shaped; one end being attached to 25 the member G; and the other end extending through registering apertures in said member and the member F to engage a cam H' portion of the latter. Thus, by relatively turning the members F and G the members H will ride up the 30 cam H' and be placed under tension sufficient to clamp both members F and G to the unit C.

The unit C together with the annular members F and G secured thereto, are mounted within the housing B by a gimbal construction having intersecting vertical and horizontal axes. This includes an annular member I having angle members J attached thereto to extend outward diametrically opposite each other in a vertical plane. The laterally extending arms J' of these members 40 J are adjacent and pivotally attached to the housing B as by means of the riveted pivot pins K. The member I is also provided with members L attached thereto and extending diametrically opposite each other in a horizontal plane. These 45 members L are pivotally attached to the member G as by riveted pivot pins M. Also, the axes of the pivots K and M intersect each other in the longitudinal axis of the unit C, and this point of intersection N is the center of the spherical segment constituting the bezel F'. Thus, the unit C can rock about the horizontal axis of the pivots M for angular adjustment in a vertical plane, while the unit C together with the annular member I can rock about the vertical axis of the pivots 50 K for angular adjustment in a horizontal plane.

The vertical and horizontal adjustments just described are accomplished by independent means accessible from the front. This comprises a screw O engaging a threaded aperture in the 55

vertically extending portion of one of the members J and having a grooved head O' for engaging a slotted bracket O² secured to the member G. Thus, by turning this screw O the unit C is 5 rocked in a vertical plane on pivots M, M with respect to the annular member I. P are spring arms centrally attached to the member J and extending obliquely therefrom to bear with their outer ends against a flange G³ on the member 10 G. These arms are normally under compression and act to hold the members G and I in each position of relative adjustment. Q is another screw engaging a threaded aperture in a bracket Q' secured to the member B. This screw is also 15 provided with a grooved head Q² which engages a slotted member Q³ on the member G, preferably formed by an outwardly extending ear on the member L. A coil spring Q⁴ surrounding the screw Q with its opposite ends engaging the 20 bracket Q' and head Q², serves to hold the members G and B in each position of relative adjustment. The heads of the screws O and Q are normally concealed by a finish ring R which surrounds the unit C and is attached to the housing 25 B by a hook R' and screw R². The inner edge of the ring R bears against the spherical surface of the bezel F' so as to form a sealing joint there- 30 within each position of adjustment.

With the construction described, after the lamp 35 has been mounted within the fender or other part of the vehicle body, it can be easily adjusted to properly direct the projected beam and to maintain the pattern thereof in proper relation to the road. Adjustment of the screw O will 40 raise or lower the center axis of the beam in a vertical plane. On the other hand, adjustment of the screw Q will shift the central axis of the beam toward one side or the other of the road. Neither of these adjustments will affect the other, 45 which facilitates proper direction of the axis of the beam to produce the desired lighting effect.

While as specifically illustrated, the lamp is 50 mounted within the fender or other part of the vehicle body, it is obvious that my improvements 45 are equally applicable to constructions where the lamp body is distinct from the vehicle body. With such constructions the member A may be omitted and the housing B suitably fashioned to the desired contour.

55 What I claim as my invention is:

1. A head lamp comprising a housing, a light 60 projecting unit within said housing and including a reflector and a patterned lens in fixed relation to each other, a gimbal mounting for said unit having intersecting vertical and horizontal axes, means for selectively adjusting the unit about said axes relative to the housing, a spherical bezel surrounding said lens centered in the 65 point of intersection of said axes and movable with said unit about said axes, and an annular member on said housing having a portion surrounding said spherical bezel in overlapping relation thereto.

2. A head lamp comprising a housing, a light 70 projecting unit within said housing and including a reflector and a patterned lens in fixed relation to each other, a gimbal mounting for said unit having intersecting vertical and horizontal axes, a spherical bezel surrounding said lens centered in the point of intersection of said axes and movable with said unit about said axes, means

outside said bezel for angularly adjusting said unit and bezel relative to the housing, and an annular member on said housing having a portion surrounding said spherical bezel in overlapping relation thereto and concealing said adjustment means. 5

3. A head lamp comprising a housing, a light 10 projecting unit within said housing and including a reflector and a patterned lens in fixed relation to each other, a gimbal mounting for said unit having intersecting vertical and horizontal axes, a spherical bezel surrounding said lens centered in the point of intersection of said axes and movable with said unit about said axes, separate means for angularly adjusting said unit and bezel relative to the housing respectively about said 15 vertical and horizontal axes located outside said bezel, and an annular finish ring on said housing surrounding said spherical bezel with the one edge cooperating with the bezel to form a sealing joint therewith and concealing said adjustment means. 20

4. A head lamp comprising a housing, a light 25 projecting unit within said housing and including a reflector and a patterned lens in fixed relation to each other, a gimbal mounting for said unit including an annular member, pivotal connections respectively between said annular member and housing and said annular member and unit, the one concentric with the horizontal axis and the 30 other concentric with an intersecting vertical axis, a spherical bezel movable about said axes with said unit and centered in the point of intersection of said axes, means for angularly adjusting said annular member with respect to said 35 housing about one of said axes, separate means for angularly adjusting said unit and bezel with respect to said annular member about the other of said axes, both of said adjusting means being located outside said bezel, and an annular finish 40 ring detachably engaging said housing having a portion overlapping said spherical bezel with one edge bearing on said bezel to form a sealing joint therewith in any one of the several positions of adjustment of said unit relative to the housing 45 and concealing said adjustment means.

5. A head lamp comprising a housing, a light 50 projecting unit within said housing and including a reflector and a patterned lens in fixed relation to each other, a gimbal mounting for said unit including an annular member, pivotal connections respectively between said annular member and housing and said annular member and unit, the one concentric with the horizontal axis and the other concentric with an intersecting vertical axis, a spherical bezel carried by said unit and centered in the point of intersection of said 55 axes, means for angularly adjusting said annular member with respect to said housing about one of said axes, separate means for angularly adjusting said unit with respect to said annular member about the other of said axes, each of said adjustment means comprising a screw with its head located to be accessible outside said bezel, and an annular finish ring detachably engaging 60 said housing having a portion overlapping said spherical bezel with one edge bearing on the bezel to form a sealing joint therewith and concealing said adjustment means. 65
